(57) **CLAIM**

The ornamental design for a children's toy, as shown and described.

DESCRIPTION

FIG. 1 is a top perspective view of a children's toy, according to the design;

FIG. 2 is a front view of the children's toy of FIG. 1;

FIG. 3 is a rear view of the children's toy of FIG. 1;

FIG. 4 is a right side view of the children's toy of FIG. 1;

FIG. 5 is a left side view of the children's toy of FIG. 1;

FIG. 6 is a top view of the children's toy of FIG. 1; and,

FIG. 7 is a bottom view of the children's toy of FIG. 1.

The broken lines shown are included for the purpose of illustrating portions of the article which form no part of the claimed design.
